UNITED STATES PATENT OFFICE

122,583

DESIGN FOR A HAIR DRYING APPARATUS

Milton H. Cearn, Chicago, Ill., assignor to C. & W. Manufacturing Co., Inc., Chicago, Ill., a corporation of Illinois

Application July 8, 1940, Serial No. 93,495

Term of patent 3½ years

To all whom it may concern:

Be it known that I, Milton H. Cearn, a citizen of the United States and a resident of Chicago, in the county of Cook and State of Illinois, have invented a new, original, and ornamental Design for a Hair Drying Apparatus, of which the following is a specification, reference being had to the accompanying drawing, forming a part thereof, and in which:

Fig. 1 is a perspective view of a hair drying apparatus showing my new design;

Fig. 2 is a fragmentary side elevational view thereof with the pedestal broken away near the top for convenience of illustration;

Fig. 3 is a top plan view of the drier portion shown in Figs. 1 and 2; and

Fig. 4 is a rear end elevational view of the drier, bracket and adjusting handle of the apparatus shown in Fig. 1, the pedestal being omitted for convenience of illustration.

The characteristic features of the design for hair drying apparatus reside in the drier, upper connecting bracket and handle having the configuration shown.

I claim:

The ornamental design for a hair drying apparatus, as shown and described.

MILTON H. CEARN.
